UNITED STATES PATENT OFFICE.

HARRY E. MARTIN, OF AUBURN, MAINE, ASSIGNOR TO UNITED SHOE MACHINERY CORPORATION, OF PATERSON, NEW JERSEY, A CORPORATION OF NEW JERSEY.

METHOD OF MAKING SHOES.

1,334,159.

Specification of Letters Patent. Patented Mar. 16, 1920.

Application filed March 1, 1918. Serial No. 219,822.

To all whom it may concern:

Be it known that I, HARRY E. MARTIN, a citizen of the United States, residing at Auburn, in the county of Androscoggin and 5 State of Maine, have invented certain Improvements in Methods of Making Shoes, of which the following description, in connection with the accompanying drawings, is a specification, like reference characters on the 10 drawings indicating like parts in the several figures.

The present invention relates to the manufacture of shoes and more particularly to improved methods of making shoes of the 15 type termed "turn shoes".

In the manufacture of turn shoes several different methods are practised to enable a counter which has been previously molded to its final shape to be incorporated in the 20 shoe. The principal object of the present invention is to provide an improved method of making turn shoes such that a previously molded counter and, if desired, a heel seat and shank member may be incorporated in 25 a turn shoe with accuracy and facility, to the end that the resulting shoe may present a better appearance and have superior fitting qualities than were obtainable by the methods heretofore practised.

30 In one of its aspects, the invention consists in assembling a shoe upper and a sole upon a last and attaching the upper to the sole completely around the sole but leaving the lining of the upper unattached to the 35 sole around the heel part, locating a previously molded counter having an inturned flange in its final, assembled relation on the sole, heel-seat nailing the shoe within the area of the heel seat, the heel seat nails 40 passing through the inturned flange of the counter and the margin of the sole, and thereafter performing the operation of turning the shoe right side out, and relasting the shoe in the usual manner. As herein 45 illustrated, the method of the invention further contemplates assembling the molded claims.

positioned on the shoe, in which case the 55 forward ends of the counter which project beyond the heel breast line of the shoe may be secured to the shank member. Also these parts may be manipulated to better advantage when assembled together. 60

In another of its aspects the invention consists in permanently securing together the margins of the counter, the shank piece, the shoe upper and the sole by a seam of fastenings after the last is withdrawn and 65 before relasting. Also, preferably, the fastenings are inserted to attach the several parts of the shoe after turning the heel portion of the shoe into position for the heel seat nailing operation to be performed to 70 the best advantage, but preferably before the shoe has been completely turned right side out. This practice permits the permanent attachment of the heel parts of the shoe at such time as they occupy their final 75 relative positions without a last being in the shoe, so that the fastenings can be inserted to better advantage and the parts secured in proper relation with greater precision. Furthermore, the lining of the shoe 80 is left free of constituent parts of the shoe so that opportunity is presented for disposing the lining of the shoe in the heel to the best advantage, it being necessary in many instances with the present practices 85 to cut the lining to eliminate the wrinkles formed in it by the second lasting operation on the shoe. Conveniently the margin of the lining is folded on the top of the shank member and covered with a sock lining after the second last is withdrawn from 90 the shoe.

The preferred manner in which the improved method of the present invention may be successfully practised and the shoe produced with the aid of this invention will now be described in connection with the accompanying drawings, and the invention will then be pointed out in the appended 95 claims.

100 Figure 1 is a perspective view of a shoe illustrating an assembled shoe upper secured to a sole in accordance with the present invention;

Fig. 2 is a perspective view illustrating 105 the manner of incorporating the counter in the shoe;

Fig. 3 is a perspective view, partly in

section, illustrating the permanent attachment of the shoe counter to the shoe; and

Fig. 4 is a perspective view of the heel portion of a shoe showing the counter dis-
position of the sock lining in the shoe.

In carrying out the method of the invention in one manner in which it has been successfully practised, a counter 2, which has been molded or otherwise conformed to its final shape prior to its incorporation in a shoe and having an inturned heel seat flange 4, together with a heel and shank member 6, are assembled preferably upon the last 5 upon which the shoe is to be made, and permanently secured in the relation they are to occupy in the completed shoe, as shown in Fig. 3. It is not necessary, of course, to use the last for the form upon which these two members are assembled, since any suitably shaped form which will enable the two members to be secured together by fastenings 9 passing through the margin of the shank member 6 and the in-turned flange 4 of the counter 2 may be used equally as well. By thus securing together the counter 2 and the shank member 6, a bottom is provided for the counter and the shank member so secured to the counter as to insure its being accurately positioned in the shoe.

The shoe upper 10 and lining 12 of the shoe are assembled upon the last 5 and secured inside out to a channeled and shouldered sole 14 in the customary manner of making turn shoes, as indicated in Fig. 1. For sewed seat work the inseam stitches 15 are continued around the heel end of the shoe, and, in order to enable the counter 2 to be arranged between the upper 10 and the lining 12 after the shoe is turned, the lining 12 is left unattached to the sole on either side a distance approximating the length of the counter wings (see Fig. 1) which ordinarily extend beyond the heel breast line, and to facilitate the disposition of the counter in the shoe upper, the lining is slit at points where it is left unattached to the sole and preferably folded back out of the way of the seam, as indicated at 16, Fig. 1. If a nailed seat is desired, the inseam 15 is terminated at approximately the heel breast line indicated at 17 and the unattached heel portion of the shoe upper is then lasted over on to the upper surface of the heel end of the sole 14 and secured by lasting tacks 18, the lining 12 in this instance being slit and left unattached to the sole from a distance forwardly of the heel breast line 17 rearwardly in a similar manner as a sewed seat.

The next step in the method consists in placing the assembled counter 2 and shank member 6 upon the sole 14 in the relative position it is to occupy in the finished shoe, and securing it to the sole temporarily by

means of one or two tacks 20 driven through the shank member 6 and clenched upon the bottom of the sole by the metal heel plate on the heel end of the last.

Following this step the first last 5 is withdrawn from the shoe and the heel end of the shoe partly turned right side out so that the shoe is in a condition such as illustrated in Fig. 3 of the drawings. In this condition of the shoe the assembled counter 2 and shank member 6 are permanently secured to the margin of the sole 14 and the overlasted portion of the heel end of the upper 10 secured by fastenings 22 preferably driven from the outer or grain surface of the sole and clenched upon the inner surface of the shank member 6. Conveniently a loose nailing machine of the type shown in United States Patent No. 1,030,775, granted June 25, 1912, on application of George Goddu, is used for this purpose, since the fastenings may be clenched on the horn 24 of such a machine, which insures a strong connection of the parts of the shoe. This attachment of the counter and shank member to the sole before the shoe is relasted serves to seat the counter firmly upon the sole and to close up the crease along the lower edge of the counter 2 and the upper surface of the sole. By partially turning the shoe for this operation the upper 10 is removed from the bottom surface of the heel end of the sole so as to leave an unobstructed nailing surface, and also the lining 12 is kept out of the interior of the counter so as to eliminate any possibility of catching the lining in the seam during the fastening operation. Also, by permanently attaching the counter and shank piece in position in the shoe before turning the forepart of the shoe, this latter operation may be readily performed without danger of displacing the counter and shank piece.

It has been found that satisfactory results may also be secured by inserting the permanent fastenings 22 from the interior of the counter 2 and clenching them upon the bottom surface of the sole, last or on a horn on the fastening machine, in which case it will be as equally advantageous to have the heel portion of the shoe half-turned, the important consideration being permanently to attach the counter and shank member to the overlasted margin of the shoe upper and the margin of the sole prior to relasting the shoe, so that the relasting operation is performed at such time as the foundation of the shoe is practically completed and the parts of the shoe secured against displacement by subsequent operations.

The next step is to complete the turning of the heel portion of the shoe in final position and also the turning of the forepart of the shoe right side out. Then the shoe is second lasted by inserting a second last 130

in the shoe, and, inasmuch as the counter and shank member is at the second lasting operation a permanent part of the shoe and properly disposed therein, this operation 5 can be performed very readily. By following the above-enumerated steps, the presence of the second last in the shoe has substantially no further utility except in so far as it is necessary to the performance 10 of the usual subsequent shoe finishing operation on the shoe, such as heelng and sole turning. After the shoe has been completed the second last is withdrawn.

It will be noted that up to this time the 15 lining 12 is unattached to the shoe. This is of considerable importance as it now enables the operator to rearrange and dispose the lining smoothly and without wrinkles in the heel end of the shoe, the lower margin 20 of the lining being then folded inwardly on to the upper side of the shank member 6. It is a common practice with the methods of making turn shoes heretofore practised to slit the lining after the second 25 last is withdrawn for the purpose of eliminating the wrinkles and uneven places in the lining due to the heel seat nailing and relasting operations as heretofore performed. Subsequently an inexpensive 30 straw-board filler piece 26 is inserted in the shoe to even up the interior walking surface in the shoe and cover the inturned margins of the heel lining and preferably a sock lining 28 is also inserted in the shoe 35 to complete the interior finish of the shoe.

It will be noted that by the practice of the above method the location of the shank member 6 to secure its greatest efficiency in the use is insured, and since the permanently 40 assembled counter 2 and shank member 6 accurately fit the last upon which the shoe is relasted, it prevents any distortion of the sole and the upper when the second last is driven into the shoe. Also, by reason 45 of the permanent attachment of the margins of the counter, shank member, upper and sole prior to relasting the shoe, a much closer rand crease may be secured, and the relative arrangement and conditions of the 50 constituent parts of the shoe are such that the shoe may be handled for this operation to better advantage and with greater facility than by prior methods.

Having fully described my invention, 55 what I claim as new and desire to secure by Letters Patent of the United States is:—

1. That improvement in methods of making shoes which consists in assembling a shoe upper inside out and a sole upon a last, 60 attaching the upper to the sole completely around the sole but leaving the lining of the shoe upper unattached to the sole around the heel portion, positioning a previously molded counter and a shank member in 65 their final relation to the sole, permanently

fastening together the margins of the sole, upper, counter and shank member, and subsequently turning and relasting the shoe.

2. That improvement in methods of making shoes which consists in assembling a 70 shoe upper inside out and a sole upon a last, attaching the upper to the sole completely around the sole, but leaving the lining of the shoe upper unattached to the sole around the heel portion, assembling a previously 75 molded counter and a shank member in their final relation, and attaching them to the sole before the shoe is turned, permanently fastening together the margins of the sole, upper, counter and shank member, and subsequently turning and relasting the shoe.

3. That improvement in the art of making shoes which consists in assembling a 80 shoe upper inside out and a sole upon a 85 last, attaching the upper to the sole completely around the sole but leaving the lining of the upper unattached to the sole around the heel part for a distance approximating the length of the counter wings, 90 assembling a previously molded counter and a shank member in their final relation, attaching the assembled counter and shank member in their final relation to the sole by fastenings passing through the margins 95 of the sole, upper, counter and shank member, and subsequently turning and relasting the shoe.

4. That improvement in methods of making shoes which consists in assembling an 100 upper inside out and a sole upon a last, sewing the upper and lining to the sole forwardly of substantially the heel breast line, securing the portion of the upper rearwardly of the heel breast line to the sole 105 by metallic fastenings but leaving the lining unattached to the sole around the heel portion and a distance forwardly of the heel breast line corresponding to the projection of the counter wings forwardly of 110 the heel breast line, permanently associating a previously molded counter and a shank member in their final relation and temporarily attaching them to the sole prior to turning the shoe right side out, permanently 115 fastening together the margins of the sole, upper, counter and shank member in their final relations, and subsequently turning and relasting the shoe and performing subsequent shoemaking operations in the usual 120 manner.

5. That improvement in methods of making shoes which consists in assembling an upper inside out and a sole upon a last, sewing the upper and lining to the sole forwardly of substantially the heel breast line, lasting the portion of the upper rearwardly of the heel breast line over on to the upper surface of the sole and securing the sole by lasting tacks but leaving the lining unat- 130

tached to the sole around the heel portion and a distance forwardly of the heel breast line corresponding to the projection of the counter wings forwardly of the heel breast line, permanently associating a previously molded counter and a shank member in their final relation and temporarily attaching them to the sole prior to turning the shoe right side out, withdrawing the last and 10 turning the heel end of the shoe right side out, securing together the margins of the sole, upper, counter and heel stiffener by fastenings inserted from the bottom surface of the sole and thereafter turning the 15 forepart of the shoe right side out and performing the subsequent operations upon the shoe in the usual manner.

6. That improvement in the art of incorporating molded counters in turn shoes which 20 consists in locating a molded counter in upright position on the heel end of the sole of a shoe which is inside out and prior to the completion of the operation of turning the shoe right side out, finally attaching the 25 counter to the shoe by inserting fastenings through the counter flange and the margin of the sole within the heel seat area of the shoe.

7. That improvement in the art of incorporating molded counters in turn shoes which 30 consists in assembling a shoe upper inside out and a sole upon a last, attaching the upper to the sole, locating a previously molded counter in upright position on the heel seat 35 portion of the shoe, driving a row of heel seat nails through the flange of the counter and the margin of the sole within the heel seat area of the shoe finally to attach the counter, turning the shoe right side out and 40 thereafter relasting the shoe and completing its manufacture.

8. That improvement in the art of incorporating molded counters in turn shoes which 45 consists in locating a molded counter in upright position on the heel end of a shoe which has been lasted and sewed while inside out, placing the shoe upon a shoe support, heel seat nailing the shoe within the area of the heel seat, the heel seat nails passing through the inturned flange of the 50

counter and the margin of the sole, and thereafter turning and relasting the shoe.

9. That improvement in the art of incorporating molded counters in turn shoes which 55 consists in lasting and sewing a shoe upper to the sole while the upper is inside out, placing a molded counter having an inturned flange upon the sole in the position in which it is to be located relatively to the sole when the shoe is turned right side out, placing the 60 shoe upon a support and, before the shoe is relasted, finally attaching the counter to the shoe by driving a plurality of fastenings through the flange of the counter and the margin of the sole within the heel seat area 65 of the shoe.

10. The method of manufacturing turned shoes of the type in which a molded counter is incorporated in the heel end of the shoe with the rear portion of the counter in contact with the inside of the upper which comprises assembling a shoe upper and lining and a sole inside out upon a last, partly attaching the upper and lining to the sole so as to leave the lining unattached around the 75 heel end of the shoe, pulling the last, turning the shoe right side out, inserting a second last in the shoe, and, prior to the insertion of the second last, applying a molded counter to the shoe, placing the shoe with 80 the heel portion at least right side out upon a support, and driving fasteners through the sole into the counter.

11. That improvement in the art of making turned shoes which comprises placing 85 upon a support the heel end of a shoe after it has been turned and a molded counter member including the molded counter proper and a strengthening member attached to the inturned flange thereof with 90 the rear of the counter located in contact with the inside of the upper, driving fasteners through the sole from the tread face thereof into the counter member and subsequently inserting a second last in the shoe 95 and completing its manufacture.

In testimony whereof I have signed my name to this specification.

HARRY E. MARTIN.
